ROBERT A. REYNOLDS, OF PORT HURON, MICHIGAN.

GRINDING-DISK.

1,109,361.

Specification of Letters Patent.

Patented Sept. 1, 1914.

Application filed June 18, 1913. Serial No. 774,299.

To all whom it may concern:

Be it known that I, ROBERT A. REYNOLDS, a citizen of the United States, residing at Port Huron, county of St. Clair, State of Michigan, have invented a certain new and useful Improvement in Grinding-Disks, and declare the following to be a full, clear, and exact description of the same, such as will enable others skilled in the art to which it 10 pertains to make and use the same, reference being had to the accompanying drawings, which form a part of this specification.

This invention relates to grinding disks and has for its object a grinding disk which 15 may be run in either direction and which has a grinding surface on either side.

A further feature is a progressively increased height of the baffles from the center of the disk to the periphery whereby the 20 grain as it progresses toward the periphery of the disk is brought into a more intimate relation with the cutting surfaces.

A still further feature is a balancing ring and lugs which are part of the casting and 25 which may be trimmed off to balance the disk upon its arbor.

In the drawings: Figure 1, is a plan view of the disk. Fig. 2, is a section on the line A—A of Fig. 1.

The grinding disk is a single casting 30 which is formed with dividing ribs *a* that are radial. Between two dividing ribs *a* are a number of ribs *d* that run parallel with the radial dividing ribs, an equal 35 number running parallel with each dividing rib. This arrangement causes a number of the ribs to meet at acute angles as at *b*. It will be noted that each side of the ribs are the same and that the sides are comparatively 40 steep. The dividing ribs *a* extend to the opening in the center of the disk, flattening out to form wings *c* that catch the grain and throw it up into the segment between the two dividing ribs. The ribs intervening between the two dividing ribs do 45 not come to the opening at the center of the disk, but stop short thereof. By reason of this arrangement of the ribs, as above described, the grinding disk may be run in either 50 direction and hence a greater amount of work secured out of one face of the disk. When one face has become worn the disk may be turned and the opposite face ex-

posed which is also capable of being run in either direction.

Baffles *e* are arranged between adjoining ribs to force the grain up where it may be caught by the sheering edges of the ribs. These baffles *e* are staggered in adjacent 55 grooves. The baffles gradually increase in height from the center to the periphery of the disk. This arrangement forces the grain into more intimate relation with the cutting surfaces of the two disks as the grain works from the center outward, hence 60 there is a gradual reduction of the grain from a coarse condition to a fine condition.

On the outside of the casting that forms the disk is an extension or balancing ring *f* and on this are still further extensions or 65 lugs *g*. Before the grinding disk is placed in the grinding head, it is centered, that is, the grinding disk is placed upon an arbor and adjusted thereto so as to balance. The lugs *g* are then trimmed off by an emery 70 wheel or other means so as to make the periphery of the disk concentric with the new center that has been established in order to 75 secure a balance. This will make the grinding disk fit into the head, but the material 80 trimmed off of the lugs will again throw the disk slightly out of balance. This balance may be restored by trimming the balancing ring. This trimming of the balancing ring 85 may take place after the disk has been set in the head inasmuch as the protruding lugs serve to space this balancing ring slightly 90 from the walls of the recess that receives the disk. A file may be inserted in this space and enough material filed off the material of the balancing ring to compensate for the material that has been trimmed off of the lugs.

What I claim is:—

A grinding disk comprising a flat surface having a plurality of ribs, baffles located in the grooves formed by the ribs, said baffles gradually rising in height from the center toward the periphery of the disk, substantially as described.

In testimony whereof, I sign this specification in the presence of two witnesses.

ROBERT A. REYNOLDS.
